MOTION PICTURE VIEWER

James R. Skinner, Cupertino, Mark O. Uitz, Mountain View, and Paul W. Hait, Saratoga, Calif., assignors to FJL Corporation, Palo Alto, Calif., a corporation of California

Filed Oct. 17, 1969, Ser. No. 19,599

Term of patent 14 years

Int. Cl. D16—99

U.S. Cl. D61—1

FIG. 1

FIG. 3

FIG. 2

FIG. 4

FIG. 5

FIG. 6

FIG. 7

FIG. 8

FIG. 1 is a side elevational view of a motion picture viewer showing our new design;

FIG. 2 is another side elevational view of the motion picture viewer opposite the side shown in FIG. 1;

FIG. 3 is a front elevational view of the motion picture viewer;

FIG. 4 is a rear elevational view of the motion picture viewer;

FIG. 5 is a top plan view of the motion picture viewer;

FIG. 6 is a bottom plan view of the motion picture viewer;

FIG. 7 is a perspective view of the motion picture viewer from a point facing the right hand side and the front of the motion picture viewer;

FIG. 8 is a perspective view of the motion picture viewer looking from a point facing the rear and the left-hand side of the same.

We claim:

The ornamental design for a motion picture viewer, as shown.
